ANSALDO & C., OF GENOA, ITALY.

GUN-CARRIAGE SHIELD AND IN THE EMBRASURES OF CASEMATES.

1,213,247.

Specification of Letters Patent. Patented Jan. 23, 1917.

Application filed June 6, 1914. Serial No. 843,443.

To all whom it may concern:

Be it known that I, PIO PERRONE, a subject of the King of Italy, residing at Rome, Italy, ship-builder, (whose post-office address is No. 366 Piazza Colonna, Rome, Italy,) have invented certain new and useful Improvements in Gun-Carriage Shields and in the Embrasures of Casemates, of which the following is a specification.

10 It is a well known expedient to protect guns mounted on carriages in casemates by means of a cylindrical armored shield projecting from the armored side of a ship or fortification through the embrasure provided for this purpose. The armored shield is constituted by armor plating attached to the gun carriage either directly or through the medium of a shield of iron or steel plating by means of connections having a certain 15 degree of elasticity, which will allow the movable armor plating on being struck by a projectile, to move back to a certain extent relatively to the said iron or steel plating and relatively to the gun carriage. In the 20 known arrangements of that kind, this displacement of the armored shield is limited only by the resistance of the elastic connections so that the impact or the repeated impacts of the enemy's projectiles are liable to 25 cause the destruction of the iron or steel plating and of the gun carriage by driving the armored shield through the embrasure into the casemate, with the further risk of the embrasure becoming entirely unprotected and thus allowing free access to the 30 enemy's projectiles.

Now the above drawbacks are avoided by the present invention which consists in a peculiar construction of the armored shield 40 and of the embrasure wherein the said shield can be displaced. According to this invention the embrasure and the armored shield are with this object, made with such profiles that any considerable displacement of the 45 shield due to the impact of a projectile has the result of causing the shield either to be arrested in the embrasure or to bear against edges, abutments or shoulders of the embrasure. In other words, the walls of the embrasure, 50 instead of forming merely a clear passage

for the shield as at present, form according to this invention an abutment or a means of engagement for the shield, which will prevent all excessive inward displacement of the shield due to external impact or shock. 55

Various constructional forms of this invention are illustrated by way of example in the accompanying drawings in which:—

Figure 1 is a diagrammatic vertical section of the embrasure of a casemate and of a gun carriage shield capable of being displaced in the embrasure, both the embrasure and the shield having the profiles hitherto usually employed. Figs. 2 and 3 are respectively a vertical section and a sectional plan, 60 on the axis of the embrasure, of an embrasure in a fixed armored casemate and of a movable armored shield constructed according to this invention. Fig. 4 is a partial vertical section showing the armored 65 shield arrested at its innermost limit of displacement. Figs. 5 and 6 show respectively in the normal position and in the innermost position of displacement another construction of an armored shield of peculiar profile 70 and of the corresponding embrasure of the fixed casemate. Fig. 7 is a partial vertical section of a third construction according to this invention. Fig. 8 is a partial vertical section of a fourth construction according 75 to this invention.

As shown in Fig. 1, the embrasure formed in the fixed armor —a— has a horizontal upper surface —a¹— and a horizontal lower surface —a²—, so that the movable armored 85 shield —b— can pass freely through the embrasure. This freedom of movement applies not only to the movements of the armored shield —b— with the iron or steel shield —c— and the gun carriage to which the armored shield is attached by elastic connections —d—, but also to all horizontal displacements relatively to the casemate which are due to the effect of impact from the outside. The surfaces —b¹— and —b²— of the 95 movable armored shield have corresponding profiles.

As shown in Figs. 2, 3 and 4 the embrasure of the fixed casemate armor —a— has an upper surface —a¹— inclined from the out- 100

side inwardly and downwardly. Its lower surface $-a^2$ is inclined in the reverse direction, that is, inwardly and upwardly. The surfaces $-b^1$ and $-b^2$ of the movable armored shield $-b$ have likewise peculiar profiles which are respectively similar to those of the corresponding surfaces of the fixed casemate. It will be readily understood (as shown in Fig. 4) that these peculiar profiles allow the movable shield $-b$ to be displaced horizontally only to a limited extent " e ". In all cases the fixed armor is caused to take the whole excessive stress due to an impact from the outside, so that the movable shield is prevented from becoming displaced toward the inside of the casemate to an extent sufficient to uncover the embrasure and allow free access to the projectiles of the enemy.

20 In the construction shown in Figs. 5 and 6 the embrasure of the fixed casemate armor has at its upper surface a rabbet or shoulder $-a^3$ the vertical outer side of which forms an abutment for the vertical inner side of a corresponding rabbet or shoulder $-b^3$ of the movable shield.

30 In the construction shown in Fig. 7, a groove or mortise $-a^4$ is provided in the upper and lower surface of the embrasure to form a guide for a tenon $-b^4$ of less width projecting from the movable shield.

35 In the construction shown in Fig. 8 the embrasure of the fixed casemate armor $-a$ has an upper outer supporting edge $-a^1$ and a lower outer supporting edge $-a^2$. The movable armored shield $-b$ is attached to the iron or steel shield $-c$ by elastic connections $-d$. The embrasure of the casemate has horizontal upper and 40 lower surfaces. The upper and lower supporting surfaces $-a^1$ and $-a^2$ of the casemate armor $-a$ form abutments against which the movable armored shield $-b$ will abut and by which it will be arrested in its inward displacement.

45 The forms of the supporting or arresting abutments provided on the fixed casemate armor for coöperating with corresponding surfaces or projections of the movable armored shield may vary, so long as they allow normally a free passage of the movable armored shield up to, and arrest its horizontal inward displacement at a determined limit.

50 Having now particularly described and ascertained the nature of my said invention and in what manner the same is to be performed, I declare that what I claim is:

55 1. A gun casemate comprising a fixed armor having an embrasure, a gun carriage internally of the fixed armor, a shield partially closing and in spaced relation to the embrasure, a resilient connection between the gun carriage and the shield, the edges

of the casemate and of the shield being 65 formed to engage each other after a limited amount of backward movement of the shield.

2. A gun casemate comprising a fixed armor having an embrasure, a gun carriage 70 internally of the embrasure, a shield partially closing the embrasure and spaced away therefrom so as to be capable of backward movement, resilient arms upon the gun carriage for supporting the shield and permitting of its backward movement under 75 excessive pressure and means for limiting the extent of backward movement of the shield.

3. A gun casemate comprising a fixed armor having an arcuate portion with a rectangular embrasure, a gun carriage movable about an axis at the point from which the arc is struck, an arcuate armored shield partially closing the embrasure and also 85 movable along said embrasure about said axis of the gun carriage in spaced relation to the fixed armor and resilient connecting means between the gun carriage and the shield, the edges of the fixed and movable 90 armor being so shaped as to arrest inward movement of the movable armor against the resistance of the resilient connecting means.

4. The combination with a gun carriage of an arcuate armored shield concentric 95 with the axis of the carriage, resilient means for mounting the shield upon the carriage and a casement having an arcuate portion positioned relatively to the shield to permit backward movement thereof and to limit the 100 extent of said movement.

5. A gun casemate comprising a fixed armor, an embrasure in the casemate of greater external than internal width, a gun carriage internally of the fixed armor, a 105 shield having a greater external than internal width, resilient means connecting the gun carriage to the shield and supporting same in spaced relation to the casemate embrasure and to permit the shield to abut 110 against said casemate embrasure under excessive external pressure.

6. A gun casemate comprising a fixed armor, an outwardly divergent embrasure in the casemate, a gun carriage internally 115 of the casemate, a shield having outwardly divergent edges and of smaller general width than the embrasure, a gun carriage internally of the embrasure, resilient means connecting the gun carriage to the shield 120 and supporting same in the casemate embrasure to permit of its abutting against the embrasure under excessive external pressure.

7. A gun casemate having an arcuate 125 embrasure, an arcuate armored shield partially closing the embrasure, a gun carriage movable about a vertical axis coinciding

with the center from which the arcuate embrasure and shield are struck, resilient means for supporting the armored shield upon the gun carriage and for resisting 5 backward movement of the shield and means upon the casemate for positively resisting backward movement of the armored shield after the operation of the resilient means.

In testimony whereof I have signed my name to this specification in presence of two ¹⁹ subscribing witnesses.

PIO PERRONE.
